RUG MARKER

Samuel C. Simonski, Philadelphia, Pa.

Application August 20, 1937, Serial No. 160,002

3 Claims.

(Cl. 40—2)

My invention relates to a marker or tag and relates more particularly to a marker employed on a rug or carpet to furnish information with respect to that article.

Heretofore, it has been customary to sew or otherwise attach a label on the back of a rug adjacent an edge or corner so that a party inspecting the rug may view the top to ascertain the manufacturer thereof, and possibly other facts, and to view the back to determine the price, size, quality and other indicia. When the rugs are on sale and piled one on top of the other or are similarly displayed, it is desirable to have sufficient data giving particular information about the rug so that the information can be easily read without pulling or moving the entire rug.

The marking device should be so located that when viewing the face of the rug one will view the marker, and after the rug is in position in the home, the marker may be turned back so that it will not be viewed.

It should also be borne in mind that the label or marker should be so constructed and secured in place that it is not likely to be lost or torn prior to the sale of the rug and that the label is pliable or flexible so that it will not tear when repeatedly bent.

It is, therefore, an object of the present invention to fulfill the above considerations in an efficient and economical style.

Another object of my invention is to embody with a flexible marker a special indicator to designate at a glance some particular feature of that article.

A further object of my invention is to provide an improved article of the character described which is simple, inexpensive to manufacture, and which is sturdy in construction.

The invention both as to details of construction and combination of parts will best be understood from the following description of a specific embodiment when read in conjunction with the accompanying drawing, in which:

Fig. 1 is a label embodying my invention.

Fig. 2 is a side elevational view of my invention as illustrated in Fig. 1 wherein one flap is folded over.

Fig. 3 is a fragmentary perspective view of my invention carrying a special or additional indicia.

Fig. 4 is a fragmentary sectional view of my invention combined with a rug looking at the tufted side of the rug.

Fig. 5 is a back view of my invention attached to a rug, which has been illustrated in Fig. 4.

Referring now in greater detail to the drawing, I show in Fig. 1 a label wherein the printing is placed on the fabric face, generally designated as A, of the label. The face A may also be woven silk or other textile material.

The printing may comprise suitable words, symbols, or trade-marks indicating the number of the article, the various sizes, the color, and the various prices.

The fact that all the printing matter may be placed on the face of the label on one operation necessarily means that there will be a saving in cost and time of printing the labels.

Therefore, the label must be so constructed that it may be bent into its final shape with the printing in the desired locations for ease of inspection.

A backing, generally designated as B, covers the rear of the label and is a rubber compound, which will adhere to any surface when it is heat treated, or the backing may be any suitable substance which will cause the label to adhere to the article to which it is affixed and which will cause the intermediate and end overlapping portions to be firmly united so that they are relatively stiff.

The label may be generally divided along the dotted lines 3, 3A into three parts 4, 5, and 6, as shown in Fig. 1.

The manufacturer's trade-mark may be imprinted on end section 4 of the label, which is then placed on the underside of the label.

On the intermediate section 5 of the label may be all the sizes in which similar articles are made and their prices, and on the third section 6 of the label may be the manufacturer's trade-mark or trade-name.

In the practical use of my invention, I fold the label along the dotted line 3A so that sections 5 and 6 are overlapping or back to back. A hot iron placed on the face 5 or upon the face 6 of the label will result in the rubber compound backing 1 firmly uniting sections 5 and 6 together. This firm uniting of the label serves not only as a stiffening member, but it prevents any wrinkling or curling of the label and, therefore, adds to the strength and attractiveness of the label, which is essential in the sale of rugs.

My label is placed upon the back 10 of the rug away from the tufts by placing the back or rubber compound portion 1 against the back 10 of the rug adjacent one of the ends or adjacent one of the corners of the rug and placing a hot

iron on the face 4. This results in the uniting of the label and the back 10 of the rug in a firm manner, and since the projecting portion of the label is stiff, the label may be easily read from either the back or the front of the rug, and the label is held in an extended position so that one examining the rug merely need pull on the extended portions 5 and 6 of the label to easily examine the indicia thereon.

10 In order to readily identify certain rugs which manufacturers desire to sell as "seconds" or closeouts, I have placed a small transversely extending tab 7 between the backing of the sections 5 and 6 of the label. By placing the small tab 7 in the position indicated, no additional adhesive, sewing, or fastening means need be used to hold the tab 7 in position. The small tab 7 between the face A and the back B of the sections 4 and 5 readily designates to the observer, without a close examination of the markers, that that particular rug is a "second" or defective in some respect. This arrangement prevents unscrupulous dealers from selling a "second" or damaged article as a perfect article, and thereby eliminates injury to the reputation and the goodwill of the manufacturer.

After the rug or carpet is sold or otherwise transferred for use, the extending display sections 5 and 6 are no longer necessary and their presence is undesirable, hence it may be conveniently and easily bent along the dotted line 3 so that it is concealed from view and does not mar the appearance of the article.

The provision of the display sections in one member, attached at a definite location to the rug by the binding rubber compound obviates the necessity for any marks on the rug or any stitches or other clipping means of attaching the marker that would be detrimental to the appearance or desirability of the article.

Although my invention has been described in considerable detail, such description is intended as illustrative rather than limiting. My invention, therefore, is not to be restricted except as

it is made necessary by the prior art and the spirit of the appended claims.

I claim as my invention:—

1. In combination with a floor covering, a label of unitary construction formed of textile material and comprising end portions connected by an intermediate portion, the face of said label having suitable indicia thereon, a rubber compound adhesive on the back of said label, one end portion and an intermediate portion having their backs 10 adhering together, the other end of the label affixed to the rear end of the floor covering, and a transversely extended tab interposed between the overlapping intermediate portion and the end portion of the label whereby said transversely 15 extending portion may be readily viewed from the side, top, and bottom of the rug.

2. A marker adapted to be associated with an article to be marked comprising a label of unitary construction and divided into substantially three parts, a rubber binding compound comprising the backing of said label and adapted to bind with other surfaces upon the application of heat, an end portion of said label overlapping and adhering to the intermediate portion of said label, 25 suitable trade-marks, various sizes, and prices printed on the face of said label, and a small tab having indicia thereon extending from between the overlapping end and intermediate portions.

3. A marker adapted to be associated with an article to be marked comprising a label of unitary construction and divided into substantially three parts, a backing of adhering material, an end portion of said label overlapping and adhering to 35 the intermediate portion of said label whereby it is relatively stiff, suitable trade-marks, various sizes and prices of the article to which it is affixed printed on the face of said label, and a small tab having indicia thereon extending from 40 between and adhering to the overlapping end and intermediate portions.

SAMUEL C. SIMONSKI.
